UNITED STATES PATENT OFFICE.

JEFFREY J. POWER, OF MADISON, WISCONSIN

MIXING-VALVE FOR INTERNAL-COMBUSTION ENGINES.

No. 887,422.

Specification of Letters Patent.

Patented May 12, 1908.

Application filed January 9, 1905. Serial No. 240,163.

To all whom it may concern:

Be it known that I, JEFFREY J. POWER, a citizen of the United States, residing at Madison, county of Dane, and State of Wisconsin, have invented new and useful Improvements in Mixing-Valves for Internal-Combustion Engines, of which the following is a specification.

My invention relates to improvements in mixing valves for internal combustion engines, with special reference to that class of devices in which a supply of liquid hydro carbon is vaporized and mixed with air while being drawn into the piston chamber of the engine by piston suction.

The object of my invention is to provide a form of construction in which the flow of air will not be materially obstructed by the devices controlling the admission of the liquid and in which a direct air passage of maximum air capacity may be used and the flow of the liquid regulated in accordance with the load, a substantially perfect mixture of maximum explosive force being secured when the engine is running at full load.

In the following description reference is had to the accompanying drawings in which,

Figure 1 is a side view of my invention partly in section on the axis of the air inlet and oil ducts. Fig. 2 is a plan view of the same. Fig. 3 is an end view. Fig. 4 is a detail view showing a valve actuating float shield. Figs. 5 and 6 are enlarged detail sectional views showing a regulating stem adapted for different variations. Fig. 7 is a detail view, partly in section, illustrating means for heating the liquid hydro carbon preparatory to its vaporization.

Like parts are identified by the same reference characters throughout the several views.

1 is a cylinder of a gas engine. The piston 2 is indicated by dotted lines.

3 is an air inlet pipe, and 4 is a feed pipe for oil or other fluid hydro carbon projecting into the air inlet pipe 3 substantially at right angles to the axis of the latter and provided with an aperture 5 through which the fluid is fed into the path of the air currents entering the engine cylinder through the pipe 3. The pipe 4 receives the hydro-carbon from any suitable source of pressure supply. A valve 6 controls the discharge of the fluid from the aperture 5. The valve 6 is provided with a stem 7 which fits loosely in a tubular aperture in the guide sleeve 8 and is

adapted to abut a regulating screw 9 which has screw threaded engagement with said sleeve and is adapted to limit the movement of the valve stem and valve.

In the construction shown, the valve stem is vertically disposed and arranged with the valve at its lower end so that it will drop by gravity to its seat, thus automatically cutting off the flow of hydro-carbon, except when lifted by some other force than the fluid itself, the weight of the valve and connected parts being sufficient to overcome the pressure of the fluid in the small aperture 5. The valve stem is provided with an inclined float shield 10 having a relative pitch in the direction of air movement and the side of the passage on which the valve is located. This float is preferably apertured and at the point of its attachment with the valve stem is almost entirely cut away to allow a free passage for the air, and whereby a portion of the liquid escaping through the aperture 5 is permitted to pass the float as it spurts through the aperture under the pressure of the supply.

In the construction shown, the float is provided with one large perforation in its outer end and three large perforations in its inner end, while the central portion of the float at each side is cut out along curved lines giving to the entire float the general outline of the figure eight. Various modifications in design and in the number and size of the perforations will suggest themselves to an ordinary mechanic, and I do not limit the scope of my invention in this respect. The style of shield shown and described is, however, simple in construction and efficient in action.

The shield is preferably rigidly secured to the valve stem and both ends of the sleeve are preferably inclined along curved lines with increasing inclination toward the ends. The walls of the air inlet pipe 3 are relied upon to prevent the valve and shield from rotating. During the suction stroke of the engine piston the air is drawn through the pipe 3 and the float shield 10 is lifted by the air current in passing, thus admitting a supply of liquid hydro carbon and concentrating the air current upon the liquid which is vaporized and thoroughly mixed with the air upon entering the engine cylinder. The perforations in the float shield sub-divide the air current and facilitate mixing the air and hydro carbon vapor.

The tubular sleeve 8 has exterior screw

threaded engagement with a fixed support 11 preferably also comprising a sleeve rigidly secured in an aperture formed in the air inlet pipe 3. The adjusting screw 9 is screwed 5 into the sleeve 8 until it strikes the valve stem 7 and is turned backwardly for a short distance and locked to the sleeve 8 by means of a thumb nut 13. An arm 14 is rigidly connected with the sleeve 8, being preferably 10 screwed thereon and locked thereto by means of a lock nut 15. By swinging the arm 14, the sleeve 8 is rotated in its screw threaded bearings in sleeve 11 and by moving the arm 14 back and forth a slight vertical variation 15 is secured in the position of the adjusting screw 9 and correspondingly in the lift of the valve 6 and valve stem 7. This adjustment is controlled by means of centrifugal governing weights 18 which are linked with a driving pulley 19 and a ring 20, both rotatably mounted on the air inlet pipe 3, as shown in the drawings, the ring 20 being free to move longitudinally along the pipe 3. The movement of the ring 20 along the pipe 3 is transmitted to the regulating arm 14 by means of a link 23, lever 24 and link 25. The lever 24 20 and arm 14 are preferably provided with a series of apertures whereby the throw of the arm 14 may be varied at pleasure.

30 27 are set screws adapted to serve as stops to limit the movement of the lever 24.

Referring to Figs. 5 and 6 it will be observed that the construction of the sleeves 8 shown in these figures is the same, with the exception that in Fig. 6 the exterior screw threads of the sleeve 8 and the interior threads of the sleeve 11 have a greater pitch than in Fig. 5. By providing sleeves with screw threads having a different pitch an extreme variation in adjustment may be secured by substituting one sleeve for another in correspondence with the size of the engine to which the device is to be applied.

It will be observed that the valve seats and 45 valves in these two views are of different sizes. By providing interchangeable valve seats and valves in sets of different sizes, I am enabled to regulate the feed of hydro-carbon without altering the distance of 50 valve movement. This is of great importance in securing an accurate control of the feed by means of the speed governor (ie, a governor the operation of which depends on the speed of the engine). It will, of course, 55 be understood that the pulley 19 is driven from the engine itself by means of a pulley 30 on the shaft 33.

Referring to Fig. 1 it will be observed that a damper valve 31 is interposed between the 60 hydro-carbon valve and the engine. This valve is mounted on a fulcrum pin 32 of the lever 24 and is actuated by said lever through the fulcrum. In this manner I am enabled to not only vary the supply of hydro-carbon to the engine, but to also vary the sup-

ply of air so that the proportions of air and hydro carbon may be kept approximately uniform under all conditions.

Referring to Fig. 7 it will be observed that the exhaust pipe 35 of the engine is provided 70 with a chamber 36. The liquid hydro-carbon is caused to flow from a reservoir 37 through a pipe 38 to a coil 39 in the chamber 36, with which coil the feed pipe 4 connects. With this arrangement the hydro-carbon 75 is heated by the exhaust gases of the engine preparatory to its introduction into the path of the air current.

Having thus described my invention what I claim as new and desire to secure by Letters 80 Patent is,

1. A mixing valve for internal combustion engines comprising the combination with the inclosing walls of an air inlet passage, of a duct for fluid hydro-carbon connected therewith; a valve controlling the flow of fluid through said aperture; and a float connected with said valve; said float being located in said passage and arranged with an inward pitch in the direction of air movement and of 85 the side of the passage occupied by the valve, and being held from rotating by the walls of the passage.

2. A mixing valve for internal combustion engines comprising the combination with the inclosing walls of an air inlet passage provided with a duct for fluid hydro-carbon; a valve controlling the flow of fluid through said duct; a float connected to operate said valve; and a guide for the valve; said float being obliquely inclined in the direction of 95 the air currents in said passage, and arranged to concentrate such currents upon the fluid hydro carbon entering through said duct.

3. A mixing valve for internal combustion engines comprising the combination with the inclosing walls of an air suction passage provided with a duct for fluid hydro-carbon; a valve controlling the flow of fluid through 100 said duct; and a float connected with the valve and arranged obliquely across the path of the air currents in said passage, said float being reduced in area adjacent to the valve and symmetrically balanced with reference 110 to the air pressure, whereby the float may be lifted by the air current without rotation.

4. A mixing valve for internal combustion engines comprising the combination with the inclosing walls of an air suction passage provided with a duct for fluid hydro-carbon; a valve controlling the flow of fluid through 115 said duct; and a float connected with the valve,—said float having an end portion obliquely disposed in the path of the air currents in said passage and a central portion partially cut away adjacent to the valve; said float being symmetrically balanced in reference to the air currents in a position to lift without rotation.

5. A mixing valve for internal combustion engines comprising the combination with the inclosing walls of an air passage provided with an inlet aperture at one side thereof for fluid hydro-carbon; a valve controlling the flow of fluid through such aperture and provided with a stem extending transversely of said passage; a float mounted on said valve stem and having an inward pitch in the direction of the side of the passage in which said valve is located; said float being arranged to receive the air pressure symmetrically, whereby the same may be lifted without rotation or lateral pressure.
- 15 6. A mixing valve for internal combustion engines comprising the combination with the inclosing walls of an air passage provided with an inlet aperture at one side thereof for fluid hydro carbon; a valve controlling the flow of fluid through such aperture and provided with a stem extending transversely of said passage; a float mounted on said valve stem and having an inward pitch in the direction of the side of the passage at which said valve is located, said float being arranged to receive the air pressure symmetrically, whereby the same may be lifted without rotation or lateral pressure; said float being provided with a series of perforations adapted to permit a portion of the air to pass through.
- 20 7. In a device of the described class, the combination with a valve for fluid hydro-carbon; a guide sleeve adjustably mounted
- in a suitable support, and arranged to guide 35 said valve; and an adjustable stop located in said sleeve and adapted to limit the movement of said valve.
8. In a device of the described class, the combination with a valve for fluid hydro- 40 carbon; a guide sleeve adjustably mounted in a suitable support, and arranged to guide said valve; and an adjustable stop located in said sleeve and adapted to limit the movement of said valve, together with a govern- 45 ing device operatively connected to adjust said sleeve and stop.
9. A mixing valve for internal combustion engines, comprising the combination with the inclosing walls of an air inlet passage pro- 50 vided with a duct for fluid; hydro-carbon leading to an inlet port at one side of the passage; and a valve controlling the flow of fluid through said duct; a stem connected with the valve and extending across the pas- 55 sage; and an actuated float connected with said stem and inclined in the direction of the air currents in said passage and in the direction of the side of the passage having said inlet port; together with a guide for said valve 60 stem; and means for regulating its movement.

In testimony whereof I affix my signature in the presence of two witnesses.
